US0D1045798S

(12) **United States Design Patent** (10) Patent No.: **US D1,045,798 S**
(45) Date of Patent: ** Oct. 8, 2024

(54) **CAPACITOR**

- (71) Applicant: **AmRad Manufacturing, LLC**,
Universal City, TX (US)
- (72) Inventor: **Robert M. Stockman**, Palm Coast, FL
(US)
- (73) Assignee: **AmRad Manufacturing, LLC**,
Universal City, TX (US)
- (**) Term: **15 Years**
- (21) Appl. No.: **29/814,809**
- (22) Filed: **Nov. 9, 2021**

CLAIM

The ornamental design for a capacitor, substantially as shown and described.

DESCRIPTION

FIG. 1 is a front top-left perspective view of a capacitor, showing my new design, taken at line 1 in FIG. 6;

FIG. 2 is a front elevation view thereof, taken at line 2 in FIG. 1;

FIG. 3 is a rear elevation view thereof, taken at line 3 in FIG. 1;

FIG. 4 is a side elevation view thereof, taken at line 4 in FIG. 1;

FIG. 5 is an opposite side elevation view thereof, taken at line 5 in FIG. 1;

FIG. 6 is a top plan view thereof; and,

FIG. 7 is a bottom plan view thereof.

The evenly-spaced broken lines represent unclaimed boundaries and form no part of the claimed design; the dot-dash broken lines in FIGS. 1 and 6 are for reference purposes only.
